UNITED STATES PATENT OFFICE

NICOLAAS ANTHONY JOHANNES VOORHOEVE, OF EINDHOVEN, NETHERLANDS, AS-
SIGNOR TO N. V. PHILIPS' GLOEILAMPENFABRIEKEN, OF EINDHOVEN, NETHER-
LANDS, A LIMITED LIABILITY COMPANY OF THE NETHERLANDS

DEVICE FOR REGULATING ALTERNATING CURRENTS *

Application filed April 19, 1927, Serial No. 185,059, and in the Netherlands May 20, 1926.

This invention has reference to a device for regulating alternating voltages in which the regulation ensues as a result of load variations.

It has already been known from the French patent specification No. 543,765 to regulate a varying working voltage by means of transformers and electron discharge devices in such manner that, if the working voltage decreases, an auxiliary voltage has been added thereto and reverted.

Such a device has for its object to permit a constant working voltage to be taken off of a varying supply voltage. It also provides for the case in which the working voltage is influenced by load impulses.

In this case the filament heating temperature is regulated by the working voltage and the anode current flows in such manner 20 through the transformer coil, that it excites in it a voltage which is opposed to the voltage prevailing in the second transformer coil, which is directly traversed by the supply current. Thus a reciprocal is insured by reason of the fact that owing to an increase of the supply voltage the counteracting voltage increases and just keeps the voltage in the load current circuit constant.

According to the invention this is insured 30 by means of a device for regulating alternating voltages in which a variable auxiliary voltage is excited between the source of current and the load by one or more booster-transformers in such manner that the voltage at the load has a previously determinable 35 characteristic, in that said auxiliary voltage is influenced by one or more electric discharge tubes the impedance of which depends on the load voltage.

According to the invention the voltage variations may cause variations in a potential drop in the transformer primary, the secondary of which influences the filament heating current of the electric discharge tubes.

It will be clear that the transformer should have a large regulating range; the normal induction must therefore be low with regard to the state of magnetic saturation. This may be effected by the use of air gaps.

The filament heating current of the electric

discharge tubes may be supplied from the secondary of a transformer the primary of which is influenced by the voltage variation which depends directly or indirectly on the load variations. According to the invention it is also possible to connect the filament heating circuit to a resistance in which voltage variations are set up in dependency of the load variations.

The accompanying drawings illustrate by way of example some schematic circuit diagrams to which the invention is applied.

Referring to Fig. 1, 1 and 2 designate input terminals to which the supply circuit is connected. The load is connected to terminals 1' and 2'. The numerals 5 and 8 designate interconnected transformers, the last named of which has two secondaries 6 and 7 which supply the filament heating current for discharge tubes 3 and 4. 9 and 10 are resistances for controlling the filament heating currents.

The schematic circuit diagram shown in Fig. 2 corresponds approximately to that of Fig. 1 but shows a modification.

The regulating action according to the invention will now be explained by reference to Fig. 1. Assume the supply voltage E to be increasing. In the first instant the load voltage will also increase. This causes an increase in supply voltage of the filaments of the tubes 3 and 4 as the filament heating transformer 8 is indirectly connected to the load voltage.

The impedance of the discharge tubes 3 and 4 will therefore decrease and hence more current will be flowing through the winding 5''.

If the auxiliary voltage which will be induced in the winding 5' by the winding 5'', is opposite to the supply voltage, the increase of the supply voltage will be opposed. It can be so regulated that it neutralizes the increase in supply voltage so that the load voltage remains about constant. The same will occur when the load current I increases. In this case the auxiliary voltage in the winding 5' will nearly balance out the auxiliary potential drop in this winding.

The action of the circuit arrangement of Figure 2 in which like numerals refer to the

same parts as in Fig. 1 is as follows: Assume the supply voltage to be increasing. In this case the working voltage will also increase at the beginning. Thus the temperature of the filaments of the diodes 3 and 4 will increase.

The impedance of said diodes decreases and the anode current thereof increases. As the tubes are connected in parallel to the winding 5" of the transformer, the potential drop in the resistance 12 increases and the current through the primary of the booster-transformer 5' decreases. The voltage on the coil 5' consequently falls and the latter is so connected that as a result the working voltage also decreases so that the latter remains substantially constant.

Now assuming that the load current is increasing, in that case the working voltage will decrease. The impedance of the discharge tubes increases as a result of the decrease of the filament heating current. The anode current of the tubes decreases and the current through the primary 5" of the transformer 5' increases. The voltage on the coil 5' consequently rises and as stated above, the latter is so connected that the working voltage increases again. This increase is so regulated that it compensates the decrease of working voltage due to the increase of the load current.

It is to be noted that in this last case (Fig. 1) an increase in the load voltage will give an increase in current flowing through winding 5". In the arrangement shown in Fig. 2 an increase in load voltage will cause a decrease of this current. Accordingly the connection of the winding 5" in Fig. 2 must be exactly the reverse as in Figure 2, so that the voltage induced in the winding 5' will be in the right direction.

It is obvious that the invention is susceptible to numerous modifications and adaptations without departing from the spirit thereof, and it is intended that the invention be limited only by the scope of the appended claims.

What I claim is:

1. A device for regulating alternating voltages, comprising main leads, a load connected across said leads, two oppositely connected discharge tubes, the said tubes being connected in parallel, a transformer, the secondary winding of said transformer being inserted in one of the leads to the load, and the primary winding thereof being included in a circuit which also comprises the said parallel connected tubes, said circuit being connected across the said main leads, and a second transformer, having its primary winding connected between said leads, the said transformer having two secondary windings each connected to the filament of a corresponding one of the said discharge tubes.

2. A device for regulating alternating voltages, comprising main leads, a load connected

across said leads, two oppositely connected discharge tubes, the said tubes being connected in parallel, a transformer, the secondary winding of said transformer being inserted in one of the leads to the load and the primary winding thereof being connected in series with the said tubes, the said series combination being connected across the said main leads, and a second transformer having its primary winding connected between the said leads, the said transformer having two secondary windings each connected to the filament of a corresponding one of the said discharge tubes.

3. A device for regulating alternating voltages, comprising main leads, a load connected across said leads, two oppositely connected discharge tubes, the said tubes being connected in parallel, a transformer, the secondary winding of the said transformer being inserted in one of the leads to the load, and the primary winding thereof being connected in parallel with the said tubes, an impedance, the said parallel combination being connected in series with said impedance across said main leads, and a second transformer having its primary winding connected between the said leads, the said transformer having two secondary windings each connected to the filament of a corresponding one of the said discharge tubes.

In testimony whereof I affix my signature, at the city of Eindhoven this 30th day of March, 1927.
